(57) **CLAIM**

The ornamental design for a desk top charger, as shown and described.

DESCRIPTION

FIG. 1 is an isometric view of an ornamental design of a desk top charger showing our new design.

FIG. 2 is a front orthographic view thereof.

FIG. 3 is a rear orthographic view thereof.

FIG. 4 is a left side orthographic view thereof.

FIG. 5 is a right orthographic view thereof.

FIG. 6 is a top orthographic view thereof; and,

FIG. 7 is a bottom orthographic view thereof.

The broken lines shown in FIGS. 1-7 are included for the purpose of illustrating environmental elements only and from no part of the claimed design.

1 Claim, 3 Drawing Sheets

FIG. 1

FIG. 2

FIG. 3

FIG. 4

FIG. 5

FIG. 6

FIG. 7

UNITED STATES PATENT AND TRADEMARK OFFICE
CERTIFICATE OF CORRECTION

PATENT NO. : Des. 504,868 S
DATED : May 10, 2005
INVENTOR(S) : Franco Lodato et al.

Page 1 of 1

It is certified that error appears in the above-identified patent and that said Letters Patent is hereby corrected as shown below:

Title page.

Item [75], Inventors, replace “James Whitaker” with -- **James Whittaker** --

Item [57], **DESCRIPTION**,

FIG. 5, replace “right orthographic” with -- right side orthographic --

Signed and Sealed this

Twenty-eighth Day of June, 2005

A handwritten signature in black ink, appearing to read "Jon W. Dudas", is centered within a rectangular dotted box.
